SPRING STRUCTURE

James Piliero, Long Island City, and Nathan Goldberg, New York, N. Y., assignors, by mesne assignments, to Dickson Wire & Cable Corporation, Long Island City, N. Y., a corporation of New York

Application February 7, 1938, Serial No. 189,032

16 Claims. (Cl. 5—248)

The present invention relates to improvements in spring structures, and has particular reference to bed springs having a top platform surface.

One of the objects of the invention is to provide a novel bed spring structure having a top platform surface defined by a rigid border frame, and a plurality of intercrossing flexible suspension members anchored at the ends to the side and end members of the frame, and tied together at the points of crossing out of direct contact and for free independent relative sliding movement.

A general object is to provide a spring structure of the foregoing character which is simple and sturdy in construction, which is highly flexible and has a floating spring action, and which is noiseless in use.

Another object is to provide new and improved means for resiliently connecting the opposite ends of the suspension members to the border frame, said means affording a strong and readily assembled anchorage, and equalizing the distribution of load on the different members.

A further object is to provide novel connector means for the suspension members at the points of crossing, whereby the members are interconnected for free independent relative sliding movement, but held and guided out of direct contact with each other to prevent wear and noise.

Still another object is to provide a new and improved bed spring structure having a sectional border frame comprising prefabricated side and end members rigidly connected at the adjacent ends by prefabricated corner pieces.

A further object is to provide a novel bed spring structure having an upper border frame in which the side and end members are reinforced to withstand the tension under load of intercrossing suspension members connected thereto and defining a top platform surface.

Another object is to provide a new and improved bed spring structure comprising a plurality of vertical coil springs arranged in longitudinal and transverse rows, and a plurality of plates spring-supported and partially closing the areas circumscribed by the upper convolutions of the coil springs.

Further objects and advantages will become apparent as the description proceeds.

In the accompanying drawings, Figure 1 is a fragmentary plan view of one corner of a bed spring structure embodying the features of our invention.

Fig. 2 is a fragmentary longitudinal vertical

sectional view taken substantially along broken line 2—2 of Fig. 1.

Fig. 3 is a fragmentary perspective view of the spring structure.

5 Fig. 4 is a detail plan view of one of the coil springs forming part of the spring structure.

Fig. 5 is a perspective view on an enlarged scale of one of the connectors for the intercrossing longitudinal and transverse suspension members, with the parts of the connector shown in disassociated relation.

Fig. 6 is a fragmentary perspective view of one of the anchors for the ends of the suspension members.

15 Fig. 7 is a detail sectional view taken along line 7—7 of Fig. 6.

Fig. 8 is a plan view on a reduced scale of the frame structure of the spring.

Fig. 9 is a transverse sectional view taken along line 9—9 of Fig. 8.

20 Fig. 10 is a fragmentary vertical transverse sectional view of the spring structure.

Fig. 11 is a fragmentary view of the underside of one of the upper corner joints of the frame structure.

25 Fig. 12 is a fragmentary view of the underside of one of the lower corner joints of the frame structure.

Fig. 13 is a fragmentary view of the underside of one of the upper corner joints of the frame structure.

30 While the invention is susceptible of various modifications and alternative constructions, we have shown in the drawings and will herein describe in detail the preferred embodiment, but it is to be understood that we do not thereby intend to limit the invention to the specific form disclosed, but intend to cover all modifications and alternative constructions falling within the spirit and scope of the invention as expressed in the appended claims.

35 The present invention relates to a spring structure having a novel platform top which has a flexible spring action with localized floating characteristics, which is sturdy and durable, and which is silent or noiseless in use. The platform top may be utilized in various types and kinds of spring structures, for example, with or without coil springs, and in spring structures having one or more spring decks.

40 Referring more particularly to the drawings, the spring structure, constituting the exemplary embodiment of the invention, is of the double deck type adapted particularly for beds and comprising a plurality of vertical double deck coil springs supported in a frame structure 2 substantially rectangular in border outline. These 45 springs may be arranged in any suitable manner,

50

for example, in longitudinal and transverse rows. Preferably, the lower deck portions of the springs 1 are cylindrical coils, and the upper deck portions are upwardly expanding spiral coils.

The frame structure 2 comprises spaced upper and lower border frames 3 and 4 and an intermediate border wire 5 at the juncture of the upper and lower spring decks. The frames 3 and 4 are of rigid metal construction, suitably braced and reenforced to withstand lateral flexure. Preferably, both frames are of angle iron construction. Thus, the frame 3 has a vertical flange 6 and an inwardly projecting horizontal flange 7 at the upper edge. Similarly, the frame 4 has a vertical flange 8 and an outwardly projecting horizontal flange 9 at the upper edge and disposed directly beneath and in parallel relation to the flange 7.

Frame sections of the general type herein exemplified have commonly been made in a single piece bent at the corners and with the ends brought together and connected by a joint in one of the transverse flights. In the present instance, each of the frames 3 and 4 is sectional in construction, and more particularly consists of prefabricated side or longitudinal and transverse or end angle iron members 10 and 11 rigidly connected at the ends by curved or arcuate cast metal corner pieces 12. At a result, the various elements of the frame can be premade in standard forms and lengths for assembly into frames of different sizes. Substantially all commercial bed springs are now made in a standard length and vary only in width. Hence, it is possible to construct frames of different standard sizes by substituting end members 11 of different lengths in assembly with standard longitudinal members 10 and corner pieces 12. The sectional construction avoids the necessity and inconvenience of bending long frame pieces, and permits the use of a relatively sharp radius at the corners of the frame shaped to conform to the top convolutions of the springs 1. Also, the corner pieces 12 being separately fabricated, need not be of the same stock as the members 10 and 11 but can be made of a hard steel to provide greater strength and rigidity.

The corner pieces 12 are angle structures to conform in shape to the frame members 10 and 11. Thus, each of the upper corner pieces is reenforced by an outer marginal depending flange or skirt 13, and each of the lower corner pieces 12 is reenforced by an inner marginal depending flange or skirt 14 (see Figs. 11 and 12). The top surfaces of the upper and lower corner pieces 12 may be formed with radial ribs 15, and the inner arcuate edges of the upper corner pieces may be serrated as indicated at 16 for ornamental purposes. The corner pieces 12 are rigidly connected at the ends, as by means of rivets 17, respectively, to the contiguous ends of the members 10 and 11. Preferably, the ends of the corner pieces 12 are formed with offset angle iron extensions 18 which overlap and interfit with the insides of the members 10 and 11, and which in effect define right-angled recesses 19 of such depth that the angle portions of the corner pieces are in alignment and hence flush with the corresponding angle portions of the frame members. Suitable shoulders 20 at the inner ends of the recesses 19 serve to locate the parts accurately in position of assembly. By the foregoing construction, the frame members 10 and 11 are connected by strong reenforced joints located at points least subjected to and

affected by the lateral stresses and strains of the frame structure 2.

Both border frames 3 and 4 are suitably braced against lateral deformation and to provide a base mounting or supporting for the springs 1. Thus, a plurality of parallel reenforcing cross bars or slats 21, preferably T-shaped in cross section, are connected at their ends to the undersides of the horizontal flanges 7 of the longitudinal frame members 10 of the frame 3 (see Fig. 9). The bars 21 are located respectively between different transverse rows of the springs 1, and substantially in the horizontal plane of the lower convolutions of the springs, and the end portions are curved upwardly and then outwardly for connection to the frame members 10. Similarly, a plurality of parallel bottom cross bars or slats 22 (see Figs. 8 to 10) are connected at their ends to the vertical flanges 8 of the longitudinal frame members 10 of the frame 4. In the present instance, the slats 22 consist of flat metal strips disposed vertically on edge and with their end portions twisted into a horizontal plane and offset upwardly into the plane of the flanges 8. At their extreme ends, the slats 22 are struck downwardly to provide flanges 22a fitting against and riveted to the flanges 8 of the lower frame members 10. The cross slats 22 respectively underlie the transverse rows of springs 1, with the exception of the end rows.

Suitable crimp wires 23, in lieu of slats, respectively underlie the transverse end rows of springs 1, and are anchored to the flanges 8 of the lower frame members 10. A plurality of longitudinal crimp wires 24 cross the slats 22 and the wires 23, and are anchored at their ends to the flanges 8 of the lower end frame members 11. In the present instance, the intermediate wires 24 extend over, and are crimped to engage or seat in notches 25 formed in the upper edges of the cross slats 22. The two outermost wires 24 extend underneath the raised opposite end portions of the slats 22 (see Fig. 3).

The slats 22 and the wires 23 and 24 serve to support the lower ends of the springs 1. In the present instance, the lower convolutions of the springs 1 in the transverse end rows are suitably interthreaded with the crimp wires 23 and 24 at the points of crossing. The lower convolutions of the side marginal springs 1 rest on the raised end portions of the slats 22 and are interthreaded with the outermost wires 24. The lower convolutions of the remaining springs 1, i. e., the springs intermediate the end and side marginal rows, are threaded through openings 26 in the slats 22, and rest on the intermediate longitudinal crimp wires 24. Between the successive springs 1 of the intermediate longitudinal rows, the crimp wires 24 are bent upwardly to form separating projections 27.

The central or intermediate convolutions of the springs 1, between the upper and lower deck portions, are suitably interthreaded with a plurality of transverse and longitudinal tie members 28 and 29 at the points of crossing. In the present instance, the tie members 28 and 29 are in the form of thin flexible straps or bands anchored to the longitudinal and transverse flights of the intermediate border wire 5, and extend closely between the central spring convolutions (see Fig. 2). The bands are crimped within the confines of the central convolutions to form downwardly offset portions 30 and 31 restraining the convolutions against relative lateral displacement.

The top convolutions of the border rows of springs 1 are rigidly anchored to the underside of the flange 7 of the frame 3 by means of rivets or 32. Spanning the area circumscribed by the upper frame 3 to form a yieldable platform sleeping surface are a plurality of parallel flexible intercrossing suspension members 33 and 34. These members may be arranged in various directions and angular relationships, and preferably are perpendicular to each other and extend transversely and longitudinally of the frame 3 intermediate the top convolutions of the springs and directly over and along the cross braces 21. The suspension members 33 and 34 also may be provided in various forms, and preferably consist of twisted strand wire cables which have been prestretched. Any suitable number of cables 33 and 34 may be employed, and in the present instance they are arranged in sets of three between the contiguous rows of springs 1 transversely and longitudinally of the frame 3. The cables 33 and 34 extend, without intermediate anchorage or interconnection, through the full dimensions of the frame 3, and more particularly are suitably connected at their opposite ends under proper tension to the flanges 7 of the upper members 10 and 11.

Preferably, the cables of each set consist of separate lengths which are separately connected to the border frame 3 by individual helical tension springs 35. Tightly clamped on each end of each cable is a split anchor sleeve 36 (see Figs. 6 and 7). In assembly, the end of the cable is extended substantially entirely through the sleeve 36, and then the sleeve is peripherally contracted into tight engagement therewith. Thereafter, the outer end of the sleeve 36 is flattened, as indicated at 37, thereby spreading the wire strands (see Fig. 7) to obtain a strong grip to withstand the cable tension. The inner ends of the springs 35 are hooked respectively through apertures 38 in the flattened ends 37 of the sleeves 36. The outer ends of each set of individual springs 35 are hooked through apertures 39 in a series of lugs or ears 40 on one longitudinal edge of an anchor plate 41. Each plate 41 is secured against the underside of the flange 7, as by means of a single central rivet 42, and is held against turning by engagement with the inside of the flange 7.

The cables 33 and 34 are strong and highly flexible, and present no sharp edges which if present would be likely to damage the overlying bedding. By anchoring the cables 33 and 34 directly to the side and end members 10 and 11 of the upper border frame 3 an increased carrying power is obtained. All of the cables substantially continuously traverse or span the full length or width of the spring structure, and are frictionally independent of each other so that the stresses are uniformly assumed and hence equalized. The side members 10 of the upper frame 3 are reenforced by the cross braces 2 to withstand the lateral stresses exerted thereon by the cables 33, particularly when under load. To prevent inward flexure by the stresses exerted by the cables 34, the end members 11 of the frame 3 are suitably strengthened as by forming each member with the major intermediate portion offset outwardly (see Fig. 8).

The sets of cables 33 and 34 at the various points of crossing are confined in parallel spaced relation and yet separated and guided for free independent action by a plurality of floating connectors 43 (see Fig. 5). If the intercrossing cables were in direct contact they would tend to

set up friction and to slap against each other, thereby resulting in highly objectionable noise and wear. The connectors 43 avoid these objections by confining the cables against whipping and slapping, and by maintaining the cables out of direct rubbing engagement.

Various forms of connectors 43 may be provided within the broad concept of the invention, and in the present instance each is shown as comprising 10 two flat plates 44 and 45 suitably secured or held together. The plates 44 and 45 are generally square in outline and are formed at the four corners with outwardly projecting apertured ears 46. Each plate is provided on one side with a plurality of parallel guides 47 adapted slidably to receive the individual cables of any one set. In the present instance, the guides 47 are formed by cutting laterally spaced sets of parallel slits 48 in the plate, and then stamping out the metal 20 between the slits of each set from one side to form a semicylindrical groove open at the ends to the other side. In assembly, the lower plate 44 is inverted with the guides 47 on the underside and disposed to receive one set of transverse cables 33. The upper plate 45 is superimposed on the plate 44 with the guides 47 on the top and angularly disposed to receive one set of longitudinal cables 34. It will be seen that the 25 intercrossing cables 33 and 34 are separated by the body portions of the plates 44 and 45, and are independently constrained for free longitudinal displacement by the respective guides 47. When the plates 44 and 45 are interattached, each serves by reason of the perpendicular disposition of the cables 33 and 34 to restrain the other against movement along the cables extending therethrough. Consequently, the cables 43 and 44 are maintained in definite arrangement without rigid interconnection and without interfering with their free individual action.

It will be evident that the cables 33 and 34, anchored to the upper frame 3 and interconnected by the connectors 43 as described, constitute in themselves a resilient spring platform surface. When used with coil springs 1, as in the present embodiment, the upper convolutions of the springs are tied in position by connection with the connectors 43. Thus, a plurality of individual helical tension springs 49 are hooked at one end respectively through the apertured corner lugs or ears 46 of each set of plates 44 and 45, and are connected at the other end to the top convolutions of the four adjacent coil springs 1. The springs 49 serve to hold the plates 44 and 45 of the various connectors 43 in close superimposed relation.

To prevent the bedding from entering the coil springs 1, a plurality of plates 50 are yieldably suspended respectively within the areas circumscribed by the top convolutions. In the present instance, each plate 50 (see Fig. 4) is of cloverleaf design, comprising four apertured radial leaves 51. Four helical tension springs 52 are connected at their outer ends to the top convolution of the associated coil spring 1, and are hooked at their inner ends through the leaves 51 to support the cloverleaf plate 50 substantially in a central position over the inner spring area.

It will be seen that we have provided a new and highly efficient spring structure. The suspension elements 33 and 34 provide a platform spring surface which is noiseless in use, which has a high carrying power, and which has a floating action, i. e., affords localized spring action. The various resilient parts of the spring structure are

effectively held in predetermined arrangement, and yet are free for independent stress and action and not subject to rubbing friction and wear. The upper frame 3 which supports the suspension elements 33 and 34 is rigid and sturdy in construction, and is strengthened to resist lateral flexure of the side and end members 10 and 11.

We claim as our invention:

1. In a spring structure, in combination, a frame structure having upper and lower border frames each comprising parallel side and end members, a plurality of springs supported from said lower border frame and arranged in longitudinal and transverse rows, a plurality of elongated flexible supporting elements extending in parallel relation in one direction across said frame structure and anchored under tension to said upper border frame, a plurality of elongated flexible supporting elements extending in parallel relation in another direction across said frame structure and said first mentioned elements, and anchored under tension to said upper border frame, a plurality of connectors tying said elements together at the various points of crossing for free independent relative sliding movement and out of direct contact with each other, and means for resiliently securing said connectors to the upper convolutions of said springs.
2. In a spring structure, in combination, a border frame having spaced parallel side and end members with depending flanges and inwardly extending horizontal flanges, a plurality of parallel sets of supporting strand wire cables extending continuously substantially throughout the length of said frame, a plurality of parallel sets of supporting strand wire cables extending continuously substantially throughout the width of said frame and crosswise of said first mentioned cables, anchor sleeves connected respectively to the ends of said cables and having outer apertured ends, a plurality of individual helical tension springs hooked respectively through said apertured ends, a plurality of anchor plates secured against the undersides of said horizontal flanges and constrained against rotation by said depending flanges, each anchor plate having a plurality of apertures and the sets of helical springs at opposite ends of said cables being hooked respectively through said plate apertures, and a plurality of connectors tying said generally longitudinal and transverse sets of cables together at the points of crossing, each connector comprising an upper plate with parallel guides on the top slidably receiving one set of cables in overlying relation to said plate, and a lower plate with parallel guides on the bottom slidably receiving a cross set of cables in underlying relation to said lower plate, and means for maintaining said plates in superimposed relation.
3. In a spring structure, in combination, a border frame having spaced parallel side and end members, a plurality of parallel sets of supporting cables extending continuously substantially throughout the length of said frame, a plurality of parallel sets of supporting cables extending continuously substantially throughout the width of said frame and generally crosswise of said first mentioned cables, a plurality of helical tension springs connecting the ends of said cables to said frame members, a plurality of connectors tying said generally longitudinal and transverse sets of cables together at the points of crossing, each connector comprising an upper plate with parallel guides on the top slidably receiving one set of cables in overlying relation to said plate, and a lower plate with parallel guides on the bottom slidably receiving a cross set of cables in underlying relation to said lower plate, and means for maintaining said plates in superimposed relation.
4. In a spring structure, in combination, a border frame having spaced generally parallel side and end members, a plurality of generally parallel flexible supporting elements extending continuously substantially throughout one general dimension of said frame and anchored at the ends under tension to said frame, a plurality of generally parallel flexible supporting elements extending continuously substantially throughout another general dimension of said frame crossing said first dimension and anchored at the ends under tension to said frame, a plurality of connectors tying said elements slidably together at the points of crossing, each connector comprising an upper plate with guide means on the top slidably receiving one of said elements in overlying relation to said plate, a lower plate with guide means on the bottom slidably receiving one of the crossing elements in underlying relation to said lower plate, and means for maintaining said plates substantially in superimposed relation.
5. In a spring structure, in combination, a border frame having spaced generally parallel side and end members, a plurality of generally parallel flexible supporting elements extending continuously substantially throughout one general dimension of said frame and anchored at the ends under tension to said frame, a plurality of generally parallel flexible supporting elements extending continuously substantially throughout another general dimension of said frame crossing said first dimension and anchored at the ends under tension to said frame, and a plurality of connectors tying said elements slidably together at the points of crossing, each connector comprising plate means separating the crossing elements and having means on opposite sides for individually guiding the crossing elements for free relative sliding movement across the opposite outside surfaces of said plate means out of direct contact with each other.
6. In a spring structure, a separator for two crossing sets of parallel suspension elements, said separator comprising a plate formed with a plurality of spaced parallel grooves in one side and opening at the ends to the other side to slidably receive one set of said elements, and a second plate formed with a plurality of spaced parallel grooves in one side inclined to said first mentioned grooves and opening at the ends to the other side to slidably receive the other set of elements, said plates being connected with their grooved faces in adjacent relation, whereby said elements are adapted to be individually guided in their respective directions for free independent longitudinal movement and the elements of said respective sets are adapted to be separated by said plates.
7. In a spring structure, in combination, a border frame having spaced generally parallel side and end members, a plurality of parallel sets of supporting cables extending continuously substantially across the area circumscribed by said frame and resiliently anchored at possible ends to said frame, a plurality of parallel sets of supporting cables extending continuously substantially across said area and crossing said first mentioned cables and resiliently anchored at opposite ends to said frame, and a plurality of cable

connecters tying said cables together respectively at the various points of crossing, each connector having two spaced sets of spaced guide passages respectively confining the cables of two inter-crossing sets to maintain the cables of each set and the two sets of cables in spaced relation for independent relative sliding movement out of direct contact with each other.

8. In a spring structure, in combination, a border frame having two spaced parallel members with inwardly extending horizontal flanges and with outwardly depending flanges, yieldable supporting means mounted within said frame and including a plurality of parallel elongated flexible supporting elements substantially spanning said frame, an anchor plate mounted against the underside of the horizontal flange and edgewise closely to the inside of the depending flange of one of said members having an aperture overlying said plate, a single connecting member extending through said aperture and serving as a sole means to secure said plate to said horizontal flange, a plurality of springs connecting said elements at one end in parallel to said plate, and means for anchoring said elements at the other end to said frame.

9. In a spring structure, a separator for two crossing sets of parallel flexible suspension elements, said separator comprising plate means formed with a plurality of parallel spaced passages on one side to receive and guide one set of said elements for independent sliding movement out of direct contact with each other and formed with a plurality of parallel spaced passages on the other side and inclined to said first mentioned passages, said last mentioned passages being adapted to receive and guide the other set of elements for independent sliding movement out of direct contact with each other and with the elements of said one set.

10. In a spring structure, in combination, a frame having two spaced parallel rigid frame members, a plurality of vertical coil springs mounted in said frame and arranged in rows across one dimension of said frame, a plurality of parallel sets of parallel stranded wire cables extending between said rows of springs in parallel relation thereto and resiliently anchored at opposite ends to said frame members, and a plurality of connecters for tying said cables to the tops of said springs, each connecter comprising plate means formed with a plurality of parallel passages adapted to receive and guide the cables of one set for independent relative sliding movement out of direct contact with each other and in definite spaced relation, and spring means for yieldably connecting each of said connecters respectively to the upper convolutions of the four adjacent coil springs.

11. In a spring structure, in combination, a frame having two spaced parallel rigid end members, a plurality of vertical coil springs mounted in said frame and arranged in rows across one dimension of said frame, a plurality of parallel sets of parallel stranded wire cables extending between said rows of springs in parallel relation thereto, a plurality of anchor plates secured to said frame members respectively in alignment with the opposite ends of said sets of cables, a plurality of individual tension springs respectively connecting the cables of each set at one end to the adjacent anchor plate, and a plurality of connecters for tying said cables to the tops of said springs, each connecter comprising plate means formed with a plurality of parallel passages

adapted to receive and guide the cables of one set for independent relative sliding movement out of direct contact with each other and in definite spaced relation, and spring means for yieldably connecting each of said connecters respectively to the upper convolutions of the four adjacent coil springs.

12. In a spring structure, in combination, a border frame having rigidly interconnected spaced end members and spaced side members, said members having an inwardly extending top flange substantially about the area circumscribed by said frame, a plurality of strand wire cables extending rectilinearly in cross directions without rigid intermediate longitudinal anchorage substantially over the span of said frame, anchor sleeves clamped respectively about the ends of said cables and each having a flat apertured free end portion, a plurality of apertured ears rigid with said flange and projecting inwardly therefrom, resilient means connecting the apertured portions of said sleeves to said apertured ears so as to tension said cables, and means connecting the intercrossing cables at the various points of crossing and serving to guide said cables individually for free relative longitudinal movement out of direct sliding contact with each other.

13. In a spring structure, in combination, a frame having two spaced parallel rigid frame members, a plurality of vertical coil springs mounted in said frame and arranged in rows across one dimension of said frame, a plurality of parallel sets of parallel stranded wire cables extending between said rows of springs in parallel relation thereto and resiliently anchored at opposite ends to said frame members, and a plurality of connecters for tying said cables to the tops of said springs, each connecter comprising plate means formed with a plurality of parallel

40

passages receiving the cables of one set and acting to maintain them out of direct contact with each other and in definite spaced relation, and spring means for yieldably connecting each of said connecters respectively to the upper convolutions of the four adjacent coil springs.

45

14. In a spring structure, in combination, a frame having two spaced parallel rigid frame end members, a plurality of vertical coil springs mounted in said frame and arranged in rows across one dimension of said frame, a plurality of parallel sets of parallel wire cables extending between said rows of springs in parallel relation thereto, a plurality of plates secured to said frame members respectively in alignment with the opposite ends of said sets of cables, a plurality of individual tension springs respectively connecting the cables of each set at one end to the adjacent plate, and a plurality of connecters for tying said cables to the tops of said vertical springs, each connecter comprising plate means formed with a plurality of parallel passages receiving the cables of one set and maintaining them out of direct contact with each other and in definite spaced relation, and spring means for yieldably connecting each of said connecters respectively to the upper convolutions of the four adjacent coil springs.

50

15. In a spring structure, in combination, a frame having two spaced parallel rigid angle end members with horizontal inwardly extending top flanges, a plurality of vertical coil springs mounted in said frame and arranged in parallel rows extending longitudinally between said end members, a plurality of parallel sets of parallel round cables extending between certain of said rows of

55

springs in parallel relation thereto, each of said sets consisting of three cables, a plurality of plates riveted to the under sides of said flanges and each plate having three eyes, said plates being located respectively adjacent the ends of said sets of cables, a plurality of individual sleeves secured respectively about the ends of said cables and each having an eye, a plurality of individual coil tension springs respectively connecting the sleeves on the ends of said cables of said sets respectively to said plates, each tension spring at one end engaging in the eye of the associated sleeve and at the other end engaging in one eye of the associated plate, and a plurality of connectors for tying said sets of cables to the top convolutions of said vertical springs, each connector comprising plate means formed with three spaced parallel recesses through which the cables of the associated set extend and in which said cables are confined out of direct contact with each other and in definite spaced relation, and individual coil tension springs yieldably connecting each of said plate means to the upper convolutions of the four adjacent vertical springs.

16. In a spring structure, in combination, a frame having two spaced parallel rigid end members and two spaced parallel rigid side members, a plurality of vertical coil springs mounted in said frame and arranged in parallel rows extend-

10 ing longitudinally and transversely between said members, a plurality of parallel sets of parallel round cables extending between certain of said rows of springs in parallel relation thereto, a plurality of plates secured to said end members and located respectively adjacent the ends of said sets of cables, a plurality of individual sleeves secured to the ends of said cables, a plurality of individual coil tension springs respectively connecting the sleeves on the ends of said cables of said sets respectively to said plates, cross members extending transversely of said cables between the transverse rows of said vertical springs and resiliently connected at their opposite ends to said side frame members, and a plurality of connectors for tying said sets of cables and said cross members together at the respective points of crossing and for tying them to the tops of said vertical springs, each connector comprising plate means formed with a plurality of parallel recesses through which the cables of the associated set extend and in which said cables are confined out of direct contact with each other and in definite spaced relation, and individual coil tension springs yieldably connecting each of said plate means to the upper convolutions of the four adjacent vertical springs.
